JOHN F. O'CONNOR, OF CHICAGO, AND JOHN R. MITCHELL, OF EVANSTON, ILLINOIS,
ASSIGNORS TO WILLIAM H. MINER, OF CHAZY, NEW YORK.

DRAFT-RIGGING YOKE.

1,286,737.

Specification of Letters Patent.

Patented Dec. 3, 1918.

Application filed August 20, 1917. Serial No. 187,212.

To all whom it may concern:

Be it known that we, JOHN F. O'CONNOR, residing at Chicago, Cook county, Illinois, and JOHN R. MITCHELL, residing at Evans-
5 ton, Cook county, Illinois, both citizens of the United States, have invented a certain new and useful Improvement in Draft-Rig-
ging Yokes, of which the following is a full, clear, concise, and exact description, ref-
erence being had to the accompanying draw-
ings, forming a part of this specification.

This invention relates to improvements in draft rigging yokes.

The object of the invention is to provide a yoke suitable for railway draft riggings and wherein is employed a two-part head suitable for connection with an ordinary U-shaped yoke strap of the rivet type.

In the drawings forming part of this specification, Figure 1 is a part vertical, longitudinal section, part side elevation of a draw bar and yoke showing our improvements in connection therewith. Fig. 2 is a horizontal, sectional view, taken on the line 2—2 of Fig. 1. Fig. 3 is a vertical, sectional view, taken on the line 3—3 of Fig. 1. Fig. 4 is a view corresponding to Fig. 1, but illustrating another embodiment of the invention. And Fig. 5 is a vertical, sectional view, taken substantially on the line 5—5 of Fig. 4.

Referring first to the construction shown in Figs. 1, 2 and 3, A designates a standard draw bar, B a U-shaped wrought iron yoke strap of the ordinary rivet type, and C—C two members which together form a hood or head to form the intermediate connection between the draw bar and the strap.

The strap B is of the usual U-shape having an upper arm 10, lower arm 11, rear connecting portion 12, filler block 13 and in-turned gibs 14—14 at the front ends of the arms 10 and 11. Each of the arms 10 and 11 is provided with the usual standardly spaced rivet holes 15—15 and it is obvious that the strap B may be an old strap or a new one.

The members C—C each comprise a vertical side wall 16, an upper horizontally extending arm 17 and a lower horizontally extending arm 18. The members C—C are duplicates and are arranged in the manner shown most clearly in Figs. 1 and 2. The lower arm 18 of one member C is provided with an upturned gib at its edge, as indicated at 19, and the upper arm of the other

member C is provided with a corresponding gib 19.

The upper and lower horizontal arms of the members C—C are also provided with standardly spaced rivet receiving holes 20—20 and the members C—C and the strap B are assembled with the ends of the arms of the strap interposed between corresponding pairs of the horizontal arms 17 and 18 of the members C. When thus assembled, short rivets 21—21 are extended through the alined rivet holes 17 and 20, as shown in Fig. 1. To connect the head formed by the members C—C to the draw bar, the vertical walls 16 of said members are slotted, as indicated at 22, to receive a coupler key 23 which is extended through a corresponding slot in the draw bar.

With the arrangement above described, it is apparent that old yoke straps may be employed with consequent saving to the users and by connecting the members C—C with the draw bar in the manner specified, all of the rivets 21—21 will be placed under double shear, thus effectively increasing the strength of the yoke connection.

Where it is desired to form a connection with a draw bar not having a coupler key slot, the construction shown in Figs. 4 and 5 is employed. In this construction, the members C'—C' are similar to the members C—C except that the upper arm 117 of one of the members and the lower arm 118 of the other of said members is provided with a transverse gib 114 to thereby form a shouldered engagement with the draw bar shoulders 30—30. In this construction, the usual gibs found on the ends of the yoke strap B' are either cut off or omitted in new constructions and elongated rivets 121—121 are extended through the members C', the arms of the yoke B' and through the usual rivet holes in the draw bar butt. In this arrangement also it will be apparent that the rivets 121 are placed under double shear due to the fact that each of the members C' has sholdered engagement with the draw bar.

We claim:

1. In a yoke, the combination with a U-shaped strap having standardly located rivet holes in the arms thereof, of a draw bar, a head comprising two like members each having a vertical portion and upper and lower horizontally extending arms, the horizon-

tally extending arms of said members being overlapped and the ends of the yoke strap arms being interposed therebetween, said horizontal arms of said members having 5 holes in alinement with the rivet holes of the strap, means extending through said holes to connect said head and strap, and means for operatively connecting both of said members and the draw bar under draft whereby 10 to place said connecting means between the head and strap under double shear.

2. In a yoke, the combination with a U-shaped strap having standardly located rivet holes in the arms thereof, of a head, said 15 head comprising two like members each having a vertical portion and upper and lower

horizontally extending arms, said horizontally extending arms of said members being overlapped and having the ends of the strap arms interposed therebetween, said arms of 20 said members having holes in alinement with said rivet holes of the strap, upper and lower sets of short rivets disposed within said holes and rigidly connecting the strap and said members, the vertical portions of said members having slots therein adapted to receive a coupler key for attachment to a draw bar. 25

In witness that we claim the foregoing, we have hereunto subscribed our names this 15 day of Aug., A. D. 1917.

JOHN F. O'CONNOR.
JOHN R. MITCHELL.
